HANDLE FOR COOKING UTENSIL

Eugene R. Russell, Chicago, Ill., assignor to McGraw-Edison Company, Elgin, Ill., a corporation of Delaware

Filed Feb. 6, 1959, Ser. No. 54,483

Term of patent 14 years

(Cl. D44—29)

Figure 1 is a perspective view showing a handle embodying my present invention;

Fig. 2 is a top plan view thereof;

Fig. 3 is a side elevation thereof; and

Fig. 4 is a bottom view thereof.

The broken line showing of a cooking utensil or fragments thereof are for illustrative purpose only.

I claim:

The ornamental design for handle for cooking utensil, substantially as shown and described.
